ATTORNEY

REAR VIEW MIRROR AND RADIO ANTENNA ASSEMBLY

Richard De Virgilis, Detroit, Mich.

Application December 27, 1955, Serial No. 555,525

4 Claims. (Cl. 343—720)

My improvement pertains to the above-named assembly for use in automobiles. More specifically, my improvement pertains to a combination of a bracket which may be mounted upon the body of an automobile, a casing pivotally supported by the bracket, which casing includes a frame, a circular rear-view mirror in the frame, and a spirally-coiled radio antenna within the casing and in a parallel relation to the mirror.

Additionally, the casing is provided with a translucent rim about the mirror and contains electrically-operated means for illumination of the rim.

The object of the invention is to eliminate the need of a conventional whip-type antenna and to utilize the casing of the rear-view mirror for the purpose of concealing therein a flexible antenna comprising a spirally-wound, flat coil of wire.

I shall now describe my improvement with reference to the accompanying drawings in which:

Fig. 1 is a side elevational view of the rear-view mirror displayed in one side of a circular casing as mounted upon a bracket, the mirror including a radio antenna within said casing;

Fig. 2 is a sectional view of the casing and the elements contained therein, in a vertical plane through the axis of the casing;

Fig. 3 is a sectional view on line 3—3 of Fig. 2;

Fig. 4 is a sectional view on line 4—4 of Fig. 2.

Similar numerals refer to similar parts throughout the several views.

The assembly includes a bracket having a base 10 and an arm 11 disposed at right angle thereto and terminating with a transversely-disposed bulbous member 12 which contains a socket 13 for reception of a short tubular member 14 supporting a casing generally identified by numeral 15.

The arm of the bracket is provided with an internal duct 16 which at the lower end is expanded radially, as shown at 17, for reception of a threaded bushing 18.

The casing 15 is circular in shape and includes a concave metal shell 19 which, in the center, is provided with a circular aperture 20, the rim portion 21 of the shell embracing an annular frame 22 which is made of a translucent plastic. The plastic may be of red color to supplement, at night, the red lights at the rear of the automobile. It is this plastic frame which encircles the mirror proper, comprising a silver-coated glass plate 23 which in the course of this specification will be called the mirror.

Fitting into the circular aperture in the shell 19, from inside, is a plastic member 24 which has the shape of a frusto-cone, the base portion of the cone being provided with a radially-expanded shoulder 25 for abutment against the inner surface of the shell about said aperture 20. The cone 24 contains an axial bore 26, and disposed therein is a bolt-like member 27 terminating with a cone tip 28 which projects from the narrow end of the cone 24. Half of the length of the bolt, remote from the

tip 28, is threaded for reception of a plurality of nuts. One of them, 29, bears against the base of the frusto cone 24 to prevent displacement of the bolt from the bore of said cone.

5 Adjoining said nut 29 is a pair of axially-aligned nuts 30, and clamped therebetween is an eyelet 31 forming a part of a metal clamp 32 embracing the insulating jacket 33 of a wire 34 to which I shall refer again.

Axially mounted upon the same bolt is a dielectric 10 disk 35 having a number of radial slots 36, the disk serving as a backing for an electrically-insulated metal wire which is wound spirally into a flat coil 37. The coil is cemented or otherwise secured against one face of the disk, as best shown in Fig. 3. One end, 38, of the wire 15 is connected to a metal eyelet 39, the eyelet being clamped between a nut 30 and the hub portion of the disk 35.

On the side facing the mirror 23, the disk carries a rubber ring 41 in a coaxial relation therewith, the ring serving as a spacer between the coil and said mirror.

20 In order to secure the disk in its place on the bolt, and to cause the disk to keep the wire 38 in contact with the adjoining nut 30, another nut, 42, is used for the purpose, the nut being disposed between the disk and the mirror 23.

25 In order to illuminate the plastic annular frame 22 from within the casing, the latter contains a light bulb 43 threaded into a socket 44 which, in turn, is held within a tubular curl 45 at the end of a metal strip 46. The strip is secured by a nut 47 to one end of the threaded end of 30 the above-mentioned member 14, and is grounded by contact therewith, as shown at A wire 48 from one terminal of the bulb is led into the duct 16 within the bracket arm 11 through said member 14. Wire 34 from the coil 37 35 is similarly led out of the casing 15 through the same member 14 and the duct 16 in the bracket arm 11 for connection, within the automobile, to a radio apparatus.

A washer 49 and a nut 50 are provided as a means of securing the base 10 of the bracket to the body of the automobile, from within, in such a manner that the wall 40 of the body of the automobile will be clamped between the base of the bracket and the nut 50 fitting over the threaded bushing 18.

When the bracket is secured to the body of the automobile, the casing may be swivelled with the tubular member 14 which fits into the socket 13 for the best viewing position, as desired by the driver of the automobile. As the wire leading from the light bulb leads to the storage battery within the automobile, it may be switched on 50 whenever desired by the driver, in which case the plastic frame would assume a red glow about the mirror and would be visible to the rear of the automobile. The metal tip 28 projecting from the casing forwardly with relation to the automobile would serve as a pick-up member for the radio antenna forming a part thereof.

55 It will be understood that the wire leading to the light bulb within the casing of the mirror may be provided with a suitable switch, and that some changes may be made in the arrangement or shape of the parts of the assembly described herein and that such changes may be made without departing from the inventive concept disclosed herein.

60 What I, therefore, wish to claim is as follows:

65 1. An assembly including a casing consisting of a circular concave shell having a central aperture, a cone shaped member of dielectric material fitting into said aperture, the member being provided with an annular frame disposed within and secured to the peripheral portion of 70 the shell in co-axial relation thereto, a metal bolt axially disposed within the casing and extending outwardly through the bore in said member of dielectric material, a

disk of dielectric material axially mounted upon said bolt, a flat, spirally wound coil of insulated wire mounted on said disk in parallel relation thereto one end of the wire being attached to said bolt, the other end of the wire extending from the casing for connection to a radio apparatus within the automobile, and bracket means supporting the casing and adapted to be affixed to the body of the automobile.

2. An assembly including a circular casing having an open side and a closed side, a flat sheet member framed in the open side, the closed side having central opening therein, a metal bolt axially disposed within the casing and projecting through said opening, outwardly, a bracket at one affixed to the casing, the other end of the bracket being adapted to be mounted upon the body of an automobile, the bracket containing a duct throughout its length a metal bolt disposed axially within the casing and projecting outwardly thereof, a flat spirally wound coil of insulated wire, axially mounted upon said bolt in parallel relation to said sheet member, one end of the wire being attached to the bolt, the other end of the wire extending from the casing and through the said duct in the bracket for connection to a radio apparatus within the automobile.

3. In combination, a circular casing open on one side and having a transverse wall at the other side, the wall being provided with an aperture at its center a cone-shaped member of dielectric material fitted into said aperture, the member being provided with an axial bore, the tapered end of the cone extending outwardly of the casing in an axial relation thereto, an annular frame of translucent dielectric material secured within the peripheral portion of the casing at its open side, a flat sheet member held within said frame, a bracket affixed to the casing for support thereof, the bracket being hollow and opening at one end into the casing, the other end of the bracket being adapted to be mounted upon the body of

an automobile, a flat substantially circular member of dielectric material axially mounted upon said bolt in a parallel relation to the mirror, a spirally wound flat coil of insulated wire mounted upon said circular member parallel thereto, a pliable ring of dielectric material mounted on the coil in coaxial relation thereto, the ring serving as a spacer between the sheet member and the coil, one end of the wire of the coil extending from the casing through the same hollow bracket to a radio apparatus within the automobile, the other end of the wire being affixed to the bolt which forms the terminal portion of the antenna.

15 4. An assembly consisting of a hollow casing open on one side and closed at the other side but provided with an aperture in its center, a mirror framed by intermediate means in the open side of the casing, a bolt axially disposed within the casing and extending therefrom outwardly through said aperture, insulating means enclosing said bolt along the portion passing through said aperture, 20 a spirally wound, flat coil of insulated wire disposed within the casing, parallel to the mirror and supported by rigid means mounted on said bolt, bracket means supporting the casing and adapted to be mounted upon the body of an automobile, one end of the wire being connected to the bolt, the other end of the wire leading to a radio apparatus within said automobile.
